UNITED STATES PATENT OFFICE.

GEORGE WARREN BLAIR, OF WABASH, INDIANA.

ANTI-RATTLER FOR THILL-COUPINGS.

SPECIFICATION forming part of Letters Patent No. 334,842, dated January 26, 1886.

Application filed December 30, 1885. Serial No. 187,072. (No model.)

To all whom it may concern:

Be it known that I, GEORGE W. BLAIR, a resident of Wabash, in the county of Wabash and State of Indiana, have invented a certain 5 new and useful Improvement in Anti-Rattlers for Thill-Couplings, of which the following is a specification.

The object of my invention is the production of an anti-rattler for thill-couplings, made 10 of plate-steel or other suitable elastic material bent upon itself and adapted to be inserted between the ears of the jack-clip, and having two curves or corrugations upon its face-front, one of which has a bearing against the thill- 15 iron.

In the accompanying drawing, forming a part of this specification, the figure is a perspective view of the anti-rattler embodying my invention.

20 A represents a steel or other suitable elastic plate, bent forward at *a*, and having a return-bend at *a'*. The outer limb, B, is formed with a rib or corrugation, *b'*, and has a curved portion, *c*, between *a'* and *b'*. From *b'* to the end 25 of the plate is a curve, *c'*, adapted to fit against the back part of the thill-iron, and by pressure against the same prevent rattling, as is well understood. To the forwardly-projecting part X of the spring-plate is secured by rivets,

or in other appropriate manner, the plate D, 30 which forms a T-head adapted to rest on top the ears of the jack-clip, thus preventing the spring from falling or working out in a downward direction, while the rib between the two curved portions *c* *c'* prevents it from working 35 out in an upward direction. By making the sharp return-curves at *a'* the spring is easily inserted between the end of the thill-iron and axle-clip.

I am aware that anti-rattlers have heretofore been made of single plates of steel bent in various forms. I therefore desire to restrict my claim to the specific device herein shown and described.

What I claim is—

45 The anti-rattler for thill-couplings hereinbefore described, made of a steel or other elastic plate, with the sharp return-curve at *a'*, the curved portions *c* and *c'*, and rib *b'* in the outer limb thereof, and having the back part 50 bent forward at *a* to form the part X, and with the plate D secured thereto.

GEORGE WARREN BLAIR.
